UNITED STATES PATENT OFFICE

2,569,729

CHILD'S ADJUSTABLE SEAT

Elton Lewis Nold, Detroit, Mich.

Application January 28, 1948, Serial No. 4,791

4 Claims. (Cl. 155—131)

1 The present invention relates to an improved child's auxiliary chair.

Prior to the present invention, various adjustable auxiliary chairs adapted for mounting on the seat of an adult's chair have been proposed for children's use. Such auxiliary chairs are adaptable for mounting on the seat or arm rest of a chair having parallel side portions and are accordingly not universally suitable for mounting on adult chairs having various angular or curvate side portions for the seat or arm rests. When such auxiliary chairs are mounted on adult chairs having non-parallel or curvate side portions, the auxiliary seat tends to slide off or tip on its mounting, with consequent danger of injury to the child.

A primary object of the present invention is to provide a sturdy, safe, and readily adjustable auxiliary chair having chair engaging legs which are vertically and laterally adjustable for mounting on the seats or arm rests of adults' chairs of various widths and heights, and which are also pivotally adjustable about vertical axes to permit adjustment to chair seats or arm rests having various angular, circular, or other curvate shapes.

Other objects of the present invention are to provide an auxiliary chair of the character described which may be readily mounted either on the floor to serve as a stool for a child, or on an adult's chair seat or arm rest; to provide positive means for preventing lateral movement of the auxiliary chair when mounted on an adult's chair; and to provide an improved adjusting means to facilitate the vertical, pivotal, and lateral adjustment of the chair engaging members.

Other objects of this invention will appear in the following description and appended claims, reference being had to the accompanying drawings forming a part of this specification wherein like reference characters designate corresponding parts in the several views.

In the drawings:

Fig. 1 is a perspective view showing a fragmentary portion of a conventional adult's chair, and also showing an auxiliary chair embodying the present invention, the auxiliary chair being elevated and tilted rearward from its mounted position;

Fig. 2 is a reduced bottom view of the auxiliary chair shown in Fig. 1, showing the legs in various positions of pivotal and lateral adjustment in phantom;

Fig. 3 is a reduced partially sectioned fragmentary front elevation of the auxiliary seat shown in Fig. 1, showing the left supporting member in

the friction engagement between the depending legs 16 and the loops 24 and 26 is adequate to prevent slipping of the supports 20-22 from their adjusted positions when a child is sitting on the seat 14. In fact the greater the load on the seat 14, the more secure will be the friction engagement. As an added precaution, a plurality of vertically spaced adjusting notches 28 are provided along the length of each leg 16 to permit a positive interlocking with one side of the respective horizontal U-shaped loop 24 at vertically spaced adjusting increments.

The upper portion of leg 16 provides the essentially perpendicularly inward extending arm 30 adapted to underlie the seat 14 and to be clamped thereto by one of the two sheet metal brackets 32. The brackets 32 provide the parallel notches 34 to engage the arms 30 and thereby to prevent accidental movement of the latter transversely to their longitudinal axes. One of each of a pair of depending stud bolts 36 embedded within the underside of the seat 14, Fig. 3, projects through one of each of the brackets 32 and provides a pivotally adjustable mounting for securing the latter to the underside of the seat 14 upon tightening the wing nut 38.

It is apparent from the structure shown that upon loosening the wing nuts 38, the arms 30 may be extended radially of the pivot axes provided by the studs 36 to permit adjustment of the chair-side engaging members 18 to chairs of various widths. Likewise the pivotal mountings of the brackets 32 permit pivotal adjustment of the seat supports about the axes of the studs 36, so that the chair-side engaging portions 18 will fit essentially flush with sides 12 which may converge toward the back part of the chair, or may be otherwise angularly disposed to the chair or provided in various curvate shapes. The pivotal adjustment of applicant's seat supporting members is of particular importance and permits an essentially universal adaptation of his auxiliary chair for mounting on the seat or arm rests of conventional chairs of various non-rectangular shapes, as for example the circular chair seat shape frequently encountered in restaurants wherein auxiliary seats of the character described are particularly useful. Also, by virtue of the pivotal adjustment of the seat supports, the portions 20-22 are readily adapted to rest firmly and squarely on the chair-seat 10 regardless of the angularity of the sides 12, so as to avoid accidental forward or rearward tipping of the auxiliary seat when a squirming child is seated thereon.

By reason of the side-engaging portions 18, the auxiliary seat is positively held against lateral slipping on the seat 10. Likewise, the portions 18, being parallel to the seat body 14, may serve as floor engaging members to permit the auxiliary chair to be used as a stool for many purposes, as for example to elevate the child before a wash bowl. In this connection, the seat body 14 is preferably covered by a suitable wear resistant, water repellent, plastic material 40, which may be readily cleaned, and which is suitably held in place as by the plurality of broad headed thumb tacks 42.

By the foregoing, applicant has disclosed a novel, simple, and readily adjustable auxiliary seat which may be safely mounted on a chair and used by a child without danger of slipping or tilting, and which also permits vertical, lateral and pivotal adjustment of the seat-supporting

members to permit adjustment thereof for chairs of various widths, heights and angular or curvate shapes.

Having thus described my invention, I claim:

- 5 1. In a child's auxiliary chair adapted to rest on the seat of an adult's chair, the combination of a seat body, paired legs depending from the lateral portions of said seat body, the lower portion of each leg being adapted to engage an adult chair seat, the upper portion of each leg providing a right angle inward extension adapted to underlie the seat body, pivotally adjustable clamping means for clamping each of said right angle extensions to the underside of said seat body in positions pivotally adjusted about a vertical pivot axis, each right angle extension being adjustable radially of said pivot axis upon loosening said pivotally adjustable clamping means.
- 10 2. The combination as claimed in claim 1 and being further characterized in that each of said legs comprises a formed rod having a pair of spaced depending portions joined at their lower extremities by a chair-side engaging portion and providing said right angle inward extension at their upper portions, and each leg provides a vertically adjustable inward projecting seat engaging support for resting on the seat of an adult's chair.
- 15 3. The combination as claimed in claim 2 and being further characterized in that each of said inward projecting seat engaging supports comprises a formed rod having a pair of spaced inward projecting portions joined at their inward extremities by a chair-seat engaging portion, and each being adjustably connected at its outer extremity to one of each of said depending leg portions for vertical adjustment therewith.
- 20 4. The combination as claimed in claim 3 and being further characterized in that each adjustable connection between said seat engaging supports and said depending leg portions includes an essentially horizontal U-shaped bend around the corresponding depending leg portion and an essentially vertical reinforcing U-shaped bend adjacent said depending leg portion, said horizontal and vertical U-shaped bends are provided by the outer extremities of said inward projections of said seat engaging supports, and internal spacing between the sides of each horizontal U-shaped bend is slightly greater than the diameter of the corresponding depending leg portion therein to permit vertical movement therebetween, each horizontal U-shaped bend is bound against vertical movement along the depending leg portions therein by friction contact therewith upon the application of torque to said chair-seat engaging portions tending to rotate said horizontal U-shaped bend about its horizontal axis of symmetry.
